(57) **CLAIM**

The ornamental design for a handle, as shown and described.

DESCRIPTION

FIG. 1 is an isometric view of a handle showing a design according to the present disclosure.

FIG. 2 is an end view of the handle.

FIG. 3 is a side view of the handle.

FIG. 4 is a second side view of the handle; and,

FIG. 5 is an opposite side view of FIG. 4 of the handle.

The shade lines shown in the drawings represent contour shading and not surface decoration. The opposite end view not shown forms no part of the claimed design.
